UNITED STATES PATENT OFFICE.

WILLIS A. SWAN, OF PORT HURON, MICHIGAN.

EVAPORATING APPARATUS.

Application filed November 11, 1919. Serial No. 337,142.

To all whom it may concern:

Be it known that I, WILLIS A. SWAN, a citizen of the United States, residing at Port Huron, county of St. Clair, State of Michigan, have invented a certain new and useful Improvement in Evaporating Apparatus, and declare the following to be a full, clear, and exact description of the same, such as will enable others skilled in the art to which it pertains to make and use the same, reference being had to the accompanying drawings, which form a part of this specification.

This invention relates to apparatus for the evaporation of liquids, and has for its object an improved organization of parts by means of which the liquid or fluid may be rapidly and efficiently subjected to the heating, agitation, and aeration, to which it is necessary to subject the liquid before the process can be considered as satisfactorily completed. My improvements herein set forth not only make possible a more compact and easily accessible mechanism, but as well enable the contemporaneous subject-
tion of the liquids to the several treatments above mentioned.

In the drawings:

Figure 1 is a perspective of my improved apparatus, with parts of the side walls of the vat or tank cut away to show details of the heating, agitating, and aerating media.

Figure 2 is a sectional elevation through the center of the tank.

Figure 3 is a plan view from above.

Figure 4 is a detail horizontal section of one form of scraper for the side walls of the tank, taken along the line 4—4 of Figure 1.

Figure 5 is a similar view of a modified or alternative form of scraper.

Fig. 6 is a detail sectional elevation of exterior circulating pump and conduits.

A indicates a vat or tank, at the bottom of which is located a steam chamber B, adapted to receive live steam through the pipe C, controlled by the valve E; from the bottom of the chamber B leads a discharge pipe D for carrying away the condensed steam, and from the bottom of the liquid-containing interior of the tank A leads a draw-off pipe A¹ controlled by a valve or faucet A². Rising from the edge of the floor of the vat A is the lowermost annular section F of the side wall. This is hollow and is adapted to receive steam through the valve J, and to discharge condensed steam past the

check valve M into the exhaust line P, either to connection with the pipe D, or to an independent discharge pipe. Above this section F is a similar hollow annular section G, the entry of steam into which is controlled by the valve K, and from which condensed steam escapes past the check valve N. The top annular section H, is similarly provided with the control valve L and check valve O. All of these sections may be firmly clamped together by vertical bolts I, passing through the top flange I¹ and the base flange I².

With its tapered lower end journaled in the center of the bottom of the tank, the hollow pipe R rises above the top of the tank to connection with an air pipe Q, which cooperates with the tapered lower end of the pipe R in rotatably centering it. The pipe Q is formed of two parts having a slip connection as shown in Fig. 2 permitting rotation of the pipe R and the attached portion of the pipe Q relative to the main part of the pipe Q which, in effect, provides a bearing for the pipe R at the upper end. The bevel gear S near the top of the pipe R is engaged by a complementary bevel gear T on the end of the shaft U, connected with a pulley U¹, or other suitable source of rotative power.

The lower portion of the pipe is perforated with a plurality of holes, which afford communication with the interior of the perforated arm X, and through the holes X¹ in which air is forced into the lower portion of the milk supply in the tank. From complementary positions about the top portion of the pipe R project radial arms W. From the end of each upper arm W and its corresponding perforated arm X is hung a scraper Z, fitted thereto in any desired manner, as by the dovetail Z¹. Pivoted to the outer faces of each scraper body are wooden or other relatively soft wiping members Y, which are yieldingly forced outwardly to engage the inner side walls of the tank by springs Y¹. This scraper may also take some other form as regards the yielding centrifugal projection of its relatively soft wiping edge, such as is shown in Figure 5, wherein the wiping member Y² is yieldingly projected by the spring Y⁴.

In operating the device, I find it of great advantage to first let the steam only into the bottom chamber B and the lowermost annular section F, then, as the liquid becomes heated, 110

steam is admitted to the second chamber G, through the valve K, and later, if the quantity of liquid to be evaporated justifies it, the opening of the valve L permits the similar heating of the top wall section H. So long as only the lower section G or the two lower sections G and H are receiving steam, the check valve N, or in the latter, the check valves N and O, prevent the steam from 10 backing into the upper wall chamber or chambers through the check valve M of the lower chamber F, past which the condensed steam at once begins to escape as soon as the chamber F has received steam through its 15 control valve J.

As soon as liquid has been placed in the tank, and steam has been turned into the lower chambers, the rotation of the hollow pipe R and its series of supporting arms W 20 and X is begun, and air under pressure is admitted through the pipe Q. This air proceeds through the holes in the lower end of the pipe R, and is distributed into all parts of the body of liquid in the tank through 25 the holes X¹ in the lower arms X. The action of the relatively soft wiping edge Y of the scrapers Z against the side surface of the tank begins as soon as the rotation of the pipe R is started, and this serves to prevent 30 an accumulation of bubbles or particles on the walls of the tank, thus avoiding scalding of the milk or other liquids, since all of it is kept in a state of constant agitation until the evaporating operation has 35 been accomplished.

Since a very important part of the operator's duties consists in closely watching the temperature of the milk within the tank, and since the rotation of the agitator and 40 aerator renders the location of a thermometer within the tank out of the question, I make the valve or faucet A² of the three way type, so that when the evaporation process is under way, it may be turned so as to close 45 the discharge outlet A³ and connect the outlet pipe A¹ with the rising section A⁴, whose top portion is bent around until it ends, as at A⁵, flush with the inner surface of the tank. In this section I install a pump, as 50 V, by which a continuous flow may be set up so as to be drawing therethrough a sample of the milk being heated. The temperature of the milk can thus be constantly watched on the thermometer V¹, mounted in the end of 55 the branch pipe V².

By the arrangement described, consisting of the three-way valve, conduits or pipe lines A⁴, V² and A⁵, a continual circulation of the fluid is obtained through operation of the 60 pump V. By use of a thermometer in the conduit the temperature of the fluid being treated is continually indicated and further, by operation of the valve A² the contents of the tank may be discharged through the 65 pipe line A³.

It is further to be observed that by the arrangement of the superimposed hollow annular sections each independently supplied with steam, an economical apparatus is provided for use with various quantities of 70 milk—that is, if only a small quantity of milk is to be treated, steam may be admitted to the lower annular section F and to the hollow base B. If a greater quantity is to be treated the sections G and F and hollow base 75 may be independently provided with steam and if the full capacity of the machine is to be utilized the additional hollow section H may be provided with live steam. By such arrangement therefore the condenser may be 80 economically operated irrespective of quantity of fluid in the tank. An additional reason for the provision of the hollow annular sections in superimposed relation substantially as shown and independently connected with the steam line is in securing a 85 uniform application of heat to the milk or other fluid being treated. One of the difficulties encountered in the use of a hollow jacketed kettle in which the heat is applied 90 at one point for the entire jacket space is that in such arrangement the heat is not uniformly applied to the fluid being treated. The jacket will be of the highest temperature at and adjacent to the point of introduction of the steam and the wall would be decreasingly heated from such point to the point of discharge. With superimposed sections of small capacity each independently 95 supplied with steam, each section of the wall 100 of the tank is of the same temperature and the body of fluid within the tank is uniformly heated. Such arrangement of superimposed sections is believed to be a new and important feature in a condenser of the 105 character herein set forth.

Having thus fully described my invention, what I claim is:

1. In evaporating apparatus, a series of 110 separable superposed and annular hollow sections, a hollow bottom, the sections and bottom being secured together and providing a cylindrical tank, each of said sections being provided with an independent inlet and outlet.

2. In evaporating apparatus, a series of 115 separable, superposed and annular hollow sections, a hollow bottom member, the said sections and bottom being secured together providing a cylindrical tank, and a rotatable agitator in the tank, each of said sections being provided with an independent inlet and outlet.

3. An evaporating apparatus comprising 120 a series of separable, superposed, annular hollow sections, a hollow bottom member, the sections and bottom member being secured together to form a cylindrical tank, an independent inlet and outlet for each of the 125 sections, a valve for each inlet, a check valve 130

in each outlet, a rotary aerator and agitator within the tank, and regulatable means for actuating the aerator and agitator and for supplying air under pressure thereto.

4. An evaporating apparatus comprising a series of separable, superposed, annular hollow sections, a hollow bottom member, the sections and bottom member being secured together to form a cylindrical tank, an independent inlet and outlet for each of the sections, a valve for each inlet, a check valve in each outlet, a rotary aerator and agitator within the tank, regulatable means for actuating the aerator and agitator and for supplying air under pressure thereto, a conduit on the exterior of the tank having an inlet and outlet in communication with the bottom and top thereof respectively, a pump in said conduit, and means for indicating the temperature of the fluid passing through the conduit.

5. An evaporating apparatus comprising a hollow walled tank, means for supplying steam to the said hollow wall, an agitator

within the tank, a conduit exteriorly of the tank having an inlet and outlet in communication with the bottom and top thereof respectively, a pump in said conduit, and a temperature indicating means subject to influence of heat of fluid passing through the conduit.

6. An evaporating apparatus comprising a hollow walled tank, means for supplying steam to the said hollow wall, an agitator within the tank, a conduit exteriorly of the tank having an inlet and outlet in communication with the bottom and top thereof respectively, a pump in said conduit, a temperature indicating means subject to influence of heat of fluid passing through the conduit, and a discharge pipe controlled by said valve.

In testimony whereof, I sign this specification in the presence of two witnesses.

WILLIS A. SWAN.
